TOP GAUGE MECHANISM FOR FASTENER SETTING MACHINES

Filed July 23, 1925

UNITED STATES PATENT OFFICE

GEORGE W. JACQUES, OF NEW BEDFORD, MASSACHUSETTS, ASSIGNOR TO ATLAS TACK CORPORATION, OF FAIRHAVEN, MASSACHUSETTS, A CORPORATION OF NEW YORK

TOP GAUGE MECHANISM FOR FASTENER-SETTING MACHINES

Application filed July 23, 1925. Serial No. 45,636.

This invention relates to top gauges more especially adapted for fastener setting machines for setting fasteners in shoe uppers and with particular relation to lacing stud setting machines in which a section of reinforcing tape is fixed by the studs to the shoe upper. The top gauge is used to determine the proper position of the shoe upper lengthwise of the line of fasteners so that the uppermost of the series will be positioned at the desired distance from the top edge of the upper when set.

As shoe uppers vary in size, it is apparent that the top gauge must be movable in order to properly cooperate therewith, and also that the spacing of the studs and the length of tape section to be fixed thereby should be varied accordingly.

In the present invention, therefore, the stud spacing mechanism has connected thereto mechanism by which the top gauge and the tape cutting mechanism are moved simultaneously therewith so that the three adjustments are properly coordinated without particular attention on the part of the operator.

The edges of shoe uppers are commonly finished by skiving and folding over and cementing the skived portions, and it is sometimes desired to fix the studs before and sometimes after the folding operation. When the setting is done before the edge folding, it is evident that the studs are set further from the edge of the work than when the folding is done first, and the top gauge which also serves as an edge gauge should be differently set for the different sequences of operation.

A further feature of this invention, therefore, resides in a gauge having a plurality of work engaging elements each adapted to cooperate with work having one certain width of margin outwardly of the line of studs to be set in the work.

For a more complete understanding of this invention together with further objects and advantageous details and combinations of parts, reference may be had to the accompanying drawings in which

Figure 1 is a fragmentary front elevation

of a stud setting machine showing the subject matter of the present invention.

Figure 2 is a side elevation of a portion of the same.

Figure 3 is a detail perspective of the top gauge and its immediate mounting, parts being broken away.

Figure 4 is a detail in perspective showing the gauge in operative relation to the folded edge of a shoe upper.

Figure 5 is a similar view showing the gauge in a different adjusted position cooperating with the unfolded edge of a shoe upper.

Figures 6 and 7 illustrate tape sections of the same length, but having four and three studs, respectively, set therein in series.

Referring to these drawings, at 1 is indicated a stud spacing adjusting lever, this lever being fulcrumed at 2 on a frame member 3 and having a toothed portion 4 thereon meshing with a gear segment 5 on one arm of a bell crank rock lever 6. This rock lever 6 is fulcrumed at 7 and its arm 8 is pivoted at 9 to a link 10 which extends to the stud spacing mechanism and may correspond to the link connecting the members c^{12} and c^{13} shown in Figure 7 of the Glass Patent No. 811,839 granted February 6, 1905 for Machines for setting lacing hooks or studs. At 20 is shown a slide carrying a portion of the stud setting mechanism comprising a punch and set 21 which is adapted to punch a piece of work lying on the work table 22 and then carry it into the position shown in Figure 1 above a stud presenting and cooperating setting mechanism 23.

In the particular mechanism shown, in parallel relation to the work table 22 is a guide bar 24 on which is slidable a tape feeding and cutting mechanism 25. This may be of any suitable type, but as herein shown is of the construction disclosed and claimed in my application for patent Serial No. 751,934, filed November 24, 1924, for Tape applying fastener setting machine. The tape passes through a slot 26 in a block 27 and at suitable times is weakened by means of a slit formed therein by a vertically reciprocable knife 28 mounted to slide across one face of

the block 27. As shown this knife is actuated through a lever 29 which is rocked at suitable times by means of the movement of a slide bar 32 having a wedge shaped end 30 which engages beneath the rear end of the lever 29. The particular manner in which this motion is effected is immaterial to the present invention, but is fully disclosed in the application hereinbefore referred to. 5 This block 27, together with the knife 28, is 10 slidable along the bar 24 to determine the distance of the knife from the punch and set 21, and thus to determine the length of the 15 tape section to be fixed by the studs to the work. Adjustment of this block to determine this length is effected automatically at the 20 same time as the spacing adjustment of the studs is effected, and for this purpose a link 40 extends from the pivot 9 to a rocker 41 to 25 which is operatively connected a rocker 42 from which extends a link 43 to the block 27. This mechanism is also shown and claimed 30 in the application hereinbefore referred to.

The rock lever 6 has fixed thereto a cam 35 roller 50 which rides in a cam slot 51 in a plate 52 which is secured to the upper end of an arm 53 fixed to a rock shaft 54. This rock shaft 54 is journaled in suitable bearings 55 extending from the main frame of the machine and carries an arm 56 having a cam head 57 at its upper end. This cam head engages a cam roller 58 journaled on a link 59 fulcrumed at 60 on a frame yoke piece 61, the upper laterally turned end of which furnishes a bearing support for the rockers 41 40 and 42. As shown best in Figure 3 the outer free end of the link 59 is slotted as at 161 and in this slot rides a guide pin 62 projecting from a rod 64 housed within a sleeve member 65. The sleeve member 65 has a slot 45 through its lower portion as at 66 for the passage of the pin 62. Within the sleeve 65 and surrounding the rod 64 is a spring 67 reacting between a collar 68 fixed to the rod 64 and a shoulder adjacent to the opposite end of the sleeve 65 by which means the rod 64 is normally held with the pin 62 adjacent to one end thereof. The opposite end of the rod 64 projecting through the sleeve carries 50 a depending pin 70 to the lower end of which is fixed a flat plate 71 carrying the top gauge 72. When the handle 1 is rocked to change the length of tape section to be fixed by the studs to the material, the rock shaft 54 is also caused to rock by the riding of the roller within the cam slot 51 and the arm 56 is thereupon moved to cause its cam head 57 to act on the roller 58 to swing the link 59 and thus 55 to advance and retract the rod 64 carrying the top gauge. The roller 58 is held in engagement with the cam head 57 by means such as a spring 75 fixed at one end as at 76 to the link 59 and at its other end to a pin 77 on 60 which the roller 50 is journaled. It will thus 65

be seen that the rocking of the handle 1 acts simultaneously to adjust the spacing of the studs, the length of the tape section which is to be made fast by a series of such studs to the work, and the top gauge which determines the setting of the first eyelet of the series in the work, and likewise determines the distance in from the edge of the work at which the row of studs will be fixed. 70

The top gauge engages the work as illustrated in Figures 4 and 5, in Figure 4 the work edge being shown as skived and folded over and cemented in place, whereas in Figure 5 the skiving has been effected but the folding has not yet been accomplished. In order that 75 the studs shall be at the same distance from the edge of the work whether the folding is accomplished before or after the setting of the studs, it is necessary that the top gauge should be correspondingly adjusted. For this 80 purpose the top gauge 72, as shown best in Figures 4 and 5, is formed as an angle piece having a relatively long arm 80 and a relatively short arm 81, either of which may be 85 presented so that the work may contact with 90 its end face. The gauge 72 is pivoted on a screw 82 to the plate 71, the gauge as shown being slotted at 83 and the plate passing therein. In order to hold the gauge in either one 95 of its adjusted positions, it is shown as provided with a pair of notches 84 on its under face with either of which may be selectively engaged a spring 85, fixed at one end, as by a screw 86, to the plate 71. When the longer 100 arm 80 of the gauge is presented in substantial alinement with the plate 85 the work may contact with its rounded end, as shown in Figure 4, this longer arm of the gauge being used when the folding of the edge of the work has been completed. When it is desired to set 105 the studs before the folding has been accomplished, the gauge 72 is turned about its pivot until the arm 81 is in substantial alinement with the plate 71, whereupon the outer rounded end of this shorter arm engages the work. 110 The difference in length between the longer arm and the shorter arm of the top gauge is 115 equal to the amount of stock which is folded back when the edge folding operation is accomplished so that whether the edge folding is done after the stud setting or before, the distance from the edge of the finished upper at which the studs are placed is the same provided the proper portion of the top gauge has been presented thereto. The gauge is thus 120 adjustable for top gauging by the translatory movement resulting from the advance or retraction of the rod 64 when the handle 1 is rocked or when the screw 88 is adjusted as hereinafter described, and it is additionally 125 adjustable by rotation so that the translatory adjustment may be accurate for different spacings of the fasteners from the work edge with which the gauge may be contacted. 130

Commonly four studs are set in each series, as shown in Figure 6, but sometimes it is desired to set only three, as shown in Figure 7, and under these conditions the length of tape section and the size of the upper being unchanged, it is necessary to increase the spacing of the studs. As, however, with the construction heretofore described, increase of such spacing would automatically increase the gauge setting and the lengths of tape section in accordance with the requirements for four studs at the increased spacing, provision is made by which the length of tape section and the position of the top gauge may be made the same as before. For this purpose the arm 56 may be made angularly adjustable about the shaft 54, as shown in Figures 2 and 3, in which a collar 85 is clamped to the rock shaft 54 and is provided with a portion 86 extending lengthwise of this shaft. Through the extension 87 of the arm 56 is threaded an adjusting screw 88 the end of which bears against the portion 86. When three studs are to be set in series the spacing lever is turned to adjust the work feeding parts to the required condition, the top gauge and tape guide moving to correspond, and then by manipulation of the adjusting screw 88, the top gauge and the tape cutting guide are returned to their former positions corresponding to the size of upper in which the three studs are to be set. Thus the top gauge is adjustable in accordance with the length of the line of fasteners to be set, having due regard to both their spacing from one another and to their number, and it is also adjustable in accordance with the spacing of the fasteners from the edge of the work, which depends on whether the edge folding has or has not been done at the time the fastenings are set.

Having thus described an embodiment of this invention it should be evident to those skilled in the art that various changes and modifications might be made therein without departing from its spirit or scope as defined by the appended claims.

I claim:

1. In a fastener setting machine, fastener setting mechanism, a top gauge, means for presenting sections of tape to be fixed by the fastenings to work, means for adjusting the spacing of the fasteners, means for regulating the length of the tape sections in accordance with said spacing, and means for automatically adjusting the position of said gauge in accordance with said spacing.

2. In a fastener setting machine, fastener setting mechanism, a top gauge, means for presenting sections of tape to be fixed by the fastenings to work, means for adjusting the spacing of the fasteners, means for regulating the length of the tape sections in accordance with said spacing, and means actuated by said spacing adjusting means for adjusting the position of said gauge.

3. In a fastener setting machine, fastener setting mechanism, a top gauge having a rotatably mounted member manually adjustable in accordance with the desired spacing of the fasteners from the work edge, and means actuatable to impart translatory movement to said member to adjust it for top gauging.

4. In a fastener setting machine, fastener setting mechanism, means for adjusting the spacing of successive fasteners, a top gauge comprising a member rotatably adjustable in accordance with the spacing of the fasteners from the work edge, means actuatable by said successive fastener spacing adjusting means for imparting translatory movement to said member relative to said fastener setting mechanism for top gauging adjustment, and other means for adjusting said top gauge independently of said successive fastener spacing adjusting means.

5. In a fastener setting machine, fastener setting mechanism, a top gauge, means for presenting sections of tape to be fixed by the fastenings to work, means for adjusting the spacing of the fasteners, means for regulating the length of the tape sections in accordance with said spacing, means for adjusting the position of said gauge, and means for adjusting said tape length regulating and gauge positioning means relative to said spacing adjusting means to provide for differences in the number of fasteners to be set in series.

6. In a fastener setting machine, fastener setting mechanism, means for adjusting the spacing of the fasteners, a top gauge, means for adjusting the position of said gauge relative to the fastener setting mechanism, and means for relatively adjusting said gauge positioning means and fastener spacing means in accordance with the number of fasteners to be set in series.

7. In a fastener setting machine, fastener setting mechanism, a top gauge, means for presenting sections of tape to be fixed by the fastenings to work, means for adjusting the spacing of the fasteners, means for regulating the length of the tape sections in accordance with said spacing, and means actuated by said spacing adjusting means for adjusting the position of said gauge, said gauge positioning and tape length regulating means including a movable member, and means for adjusting said member relatively to said spacing adjusting means in accordance with the number of fasteners to be set in series.

8. In a fastener setting machine, fastener setting mechanism, a top gauge having a portion engageable with the work edge, means for supporting said gauge for adjustment toward and from said mechanism in accordance with the length of the line of fasteners to be set, and means by which said gauge portion may be adjusted to properly

cooperate with either a folded or unfolded work edge.

9. In a fastener setting machine, fastener setting mechanism, a top gauge, means for
5 adjusting the spacing of the fasteners set by
said mechanism for simultaneously adjusting
the position of said gauge to correspond
thereto, means for adjusting the position of
10 said gauge in accordance with the number of
fasteners to be set in series, and means by
which said gauge may be adjusted to properly
cooperate with either a folded or an un-
folded edge.

15 In testimony whereof I have affixed my
signature.

GEORGE W. JACQUES.
